UNITED STATES PATENT OFFICE.

BURT YOAKUM, OF KANSAS CITY, KANSAS.

HEADLIGHT.

1,078,891.

Specification of Letters Patent. Patented Nov. 18, 1913.

Application filed July 25, 1913. Serial No. 781,178.

To all whom it may concern:

Be it known that I, BURT YOAKUM, a citizen of the United States, residing at Kansas City, in the county of Wyandotte and State 8 of Kansas, have invented a certain new and useful Improvement in Headlights, of which the following is a specification.

My invention relates to improvements in headlights.

- 10 The object of my invention is to provide a cheap, simple, durable and efficient mechanism for removably holding the pane of glass of a headlight, so that the pane may be readily removed or inserted, and which will 15 eliminate the breakage of the pane, due to its being displaced through jolting to which the headlight may be subjected.

In the preferred form of my invention, which is illustrated in the drawing—Figure 20 1 is a front elevation of a headlight provided with my improvement. Fig. 2 is a side elevation of the same. Fig. 3 is an enlarged elevation of one of the closures, shown detached. Fig. 4 is an enlarged, horizontal 25 section, on the line *a—b* of Fig. 2, Fig. 5 is a vertical section, on the line *c—d* of Fig. 2, Fig. 6 is an enlarged cross section on the line *e—f* of Fig. 1, Fig. 7 is an enlarged cross section, on the line *g—h* of Fig. 1.

30 Similar characters of reference designate similar parts in the different views.

1 designates the body of the headlight and 2 a casing at the forward end of the headlight, and provided at one side edge with a 35 slot 3, Figs. 6 and 7, through which is adapted to be inserted a pane of glass 4, which when inserted, rests in grooves provided therefor at the upper and lower end of the casing and at the side edge which is opposite 40 to that containing the slot 3, as indicated by dotted lines in Fig. 1. These grooves are disposed in the same plane as the slot 3.

After the pane 4 has been inserted, it is retained in place by means of a closure, 45 which is vertically removable from the casing and is preferably slidably interlocked therewith in the following manner:—The body 5 of the closure is provided at opposite vertical edges with inwardly extending 50 flanges 6, which form grooves for receiving respectively two vertical flanges 7, Fig. 7, which extend in opposite directions outwardly at right angles from the casing 2.

The upper end of the closure 5 is provided with an inwardly turned lip 8, which rests upon the casing 2 and closes the upper

end of the slot 3, and supports the closure in the closed position. Preferably the lip 8 is provided at opposite side edges, as shown in Figs. 1, 3 and 6, with downwardly turned flanges 9, which embrace opposite sides of the casing 2.

To remove a pane the closure 5 is slipped upwardly out of engagement with the flanges 7, thereby opening the slot, so that the pane can be slipped outwardly therethrough. After a pane has been inserted the closure is slipped back in position, as shown in Fig. 1, and in this position will securely retain the pane within the casing.

70 By reason of the closure 5 being vertically slidably mounted on the flanges 7, any jolting to which the headlight may be subjected will tend to retain the closure in its seat and it cannot thereby be jolted or rubbed by the pane from the closed position. As commonly mounted in headlight casings, the panes are slipped in from the top, and the panes and closures are liable to displacement from jolting, which displacement results in the breaking of the pane. With my construction, the danger of breakage from this cause is eliminated.

75 The side panes 10, are removably mounted in casings 11, in substantially the same manner as is the pane 4 in the casing 2. The casing 11, as shown in Fig. 4, is provided at one side edge with a slot 12, corresponding to the slot 3, already described, and the casing at opposite sides of said slot is provided with lateral, vertical, flanges 13, which extend outwardly in opposite directions, and which correspond to the flanges 7, and which are slidably mounted in two 80 grooves, provided in opposite sides of a closure 15, having inwardly turned flanges 14, at opposite side edges, as shown in Fig. 4, which embrace the flanges 13. The closure 15, at its upper end, is provided, as shown in Figs. 2 and 5, with an inwardly turned lip 16, which rests upon the casing 11, closes the slot 12, at its upper end and supports the closure 15 in the closed position.

85 The operation of the closure 15 is the same as the closure 5.

If desired, the lip 8 may have its joint with the body 5, reinforced by an angular reinforcing plate 17, as shown in Figs. 1 and 2.

90 I do not limit my invention to the structures illustrated and described, as modifications, within the scope of the appended

claims, may be made without departing from the spirit of my invention.

Having thus described my invention, what I claim and desire to secure by Letters 5 Patent is:—

1. In a headlight, a casing for holding a pane of glass, provided at one side edge with a slot for receiving the pane, and provided at the opposite side edge and at the 10 bottom with grooves disposed in the same plane as said slot, for receiving the pane inserted through said slot, and an upwardly removable slidable closure having means for interlocking with said casing for closing 15 said slot and retaining the pane inserted in said groove, the closure having at its upper end a lip which, in the closed position, rests upon the casing and supports the closure.
2. In a headlight, a casing for holding a 20 pane of glass provided at one side edge with a slot, the casing at opposite sides of said

slot having flanges extending vertically and at right angles outwardly, the casing at its other side edge and at its bottom being provided with grooves disposed in the same 25 plane as said slot, for receiving and supporting a pane inserted into said slot, and an upwardly removable closure slidable on said flanges and having two oppositely disposed grooves adapted to receive said flanges, the 30 closure at its upper end having a lip which, in the closed position, rests upon the casing, closes the top of the slot and supports the closure.

In testimony whereof I have signed my 35 name to this specification in presence of two subscribing witnesses.

BURT YOAKUM.
